(No Model.)

E. Z. MACK.
WIRE TIGHTENER.

No. 413,074.

Patented Oct. 15, 1889.

his Att'y.

UNITED STATES PATENT OFFICE.

EDWIN Z. MACK, OF MARSHALLTOWN, IOWA.

WIRE-TIGHTENER.

SPECIFICATION forming part of Letters Patent No. 413,074, dated October 15, 1889.

Application filed June 27, 1889. Serial No. 315,782. (No model.)

To all whom it may concern:

Be it known that I, EDWIN Z. MACK, a citizen of the United States, residing at Marshalltown, in the county of Marshall and State of 5 Iowa, have invented certain new and useful Improvements in Wire-Tighteners; and I do hereby declare the following to be a full, clear, and exact description of the invention, such as will enable others skilled in the art to which 10 it appertains to make and use the same.

My invention relates to a device for applying wire bands to hose and tightening and securely fastening the same therearound.

My object is to produce more simple and 15 efficient means for accomplishing this result than have hitherto been in use.

With these ends in view my invention consists in the peculiar features and combinations of parts more fully described herein- 20 after, and pointed out in the claims.

Referring to the accompanying drawings, Figure 1 is a side elevation of my device; Fig. 2, a front elevation showing the spring-cams set in position; Fig. 3, a similar view 25 showing the cams released and grasping the ends of the wire in the act of tightening them around the hose, and Fig. 4 a view of a hose-coupling in which the hose has been fastened on the coupling by my improved tool.

30 The reference-letters A and B represent the two handles or arms of the device. They are pivoted together at c, and a hole or perforation d is bored through the frictional bearing-plates a b of the arms to form a cutter for 35 clipping off the ends of the wire. A similar cutter for smaller wire is formed on the opposite side of the pivot c by a perforation e in the plate b and a recess f, cut out of the plate a. The two handles A B are normally urged 40 away from each other by the semicircular flat spring C, interposed between them. Beyond the pivot c these arms are formed into enlarged heads D E, having oblique inner lateral faces g h.

45 The handles A B, in conjunction with the pivot c, co-operate as a pair of first-class levers to actuate the heads D E toward and away from each other in the tying operation, to be more fully described hereinafter. The 50 outer faces or surfaces i j of these heads are provided with flanges k l, located diagonally opposite each other, their inner shoulders m

n being grooved to receive the wire ends. Posts o p and pivots r s project from the surfaces i j. A pair of cams F G are pivoted on 55 the pivots r s, respectively. The inner convex edges of these cams are provided with teeth t u, which are cut at an angle of about forty-five degrees to their respective pivots, while their outer extremities are provided 60 with tapered arms v w. The ends of these arms are adapted to fit in apertures or depressions x y, formed in the lateral faces g h of the heads. When the tool is not in use, the points project beyond the outer sides of 65 the heads D E and hold the faces g h apart, as shown in Fig. 1. These cams F G are spring-actuated toward the grooved shoulders m n of the flanges k l by means of the springs a' b', secured in the posts o p, and bearing 70 against the outer edges of the cams. The grooved shoulders m n are provided with series of serrations m' n', for the purpose of more tightly holding the wire.

It will be seen that the pivot c forms a common fulcrum for the levers or handles A B, and that the axes of the spring-actuated cams F G are arranged at right angles, or substantially so, to the pivot c, and that the planes of the faces i j lie on the same plane as the 80 pivot. These peculiarities will be more readily observed in Fig. 1.

The preferred manner of constructing my device having been set forth, I will now proceed to describe its operation.

85 The length of wire required to span the hose (either once or twice, as desired) is first determined and cut off by means of the cutters in the plates a b. The operator then spans the hose, leaving the wire ends extending in 90 alignment with each other a sufficient distance after crossing to be grasped in the tightening-tool. The cams F G are then set by pressing their inner ends toward each other and causing them to enter the depressions x y in the lateral faces g h. The tightener is then applied to the wire ends, so that they will lie in the grooved shoulders m n between the same and the toothed portion of the cams. The handles A B are now pressed toward each other, and the cams will thus be released from the depressions x y and forced against the wire by the springs a' b'. As the handles are further brought together, the cams

tighten on the wire, as the teeth of the same are cut at an angle, as described, and the wire at the same time will be tightened around the hose. It is apparent that the more pressure brought to bear on the handles the tighter the cams will hold the wires, for this operation will spread the heads D E, which form the short arms of the levers, farther apart. If the wire has not been sufficiently tightened, when the handles have been brought together, they can be released, and the cams will slip back and take a fresh hold on the wire. When the wire has been sufficiently tightened around the hose, the tightener is given a turn, which twists the ends of the wires around each other, and thus couples them. The handles can now be released and the tool pulled off the wires. The surplus wire is cut off by the cutters in the plates a b and the ends hammered down against the hose, and a simple, strong, and absolutely water-tight coupling has been made.

It is evident that many slight changes which might suggest themselves to a skilled mechanic could be resorted to without departing from the spirit and scope of my invention; hence I do not limit myself to the precise construction herein shown.

Having thus described my invention, what I claim as new, and desire to secure by Letters Patent, is—

1. In a wire-tightener, a pair of levers provided with cams upon their short arms, said cams having their axes arranged at right angles to the fulcrum of the levers, in combination with gripping-surfaces against which the wires are held by the cams, in the manner and for the purpose substantially as described.

2. In a wire-tightener, a pair of levers provided with spring-actuated cams upon the

outer extremities of the short arms thereof, said cams having their axes substantially at right angles to the fulcrum of the levers, and gripping-surfaces against which the wires are held by the cams, in the manner and for the purpose set forth.

3. In a wire-tightener, a pair of levers provided with spring-actuated cams, in combination with gripping-surfaces against which the cams bear and arms upon the cams arranged to engage the opposite arms of the levers, whereby the cams are held open for the reception of the wires and are released and thrown into action when receding from each other, in the manner and for the purpose described.

4. The combination, in a wire-tightener, of a pair of spring-actuated levers provided with spring-actuated cams upon their short arms, gripping-surfaces for the cams, and arms upon the cams arranged to engage oppositely-located recesses in the levers, all arranged and adapted to operate in the manner and for the purpose substantially as described.

5. In a wire-tightener, the combination of a pair of spring-actuated arms, enlarged heads on the ends of said arms having depressions formed therein, cams pivoted on said heads and arranged to be set by engaging said depressions, springs for actuating said cams, and grooved shoulders against which they bear, all arranged and adapted to operate as described.

In testimony whereof I affix my signature in presence of two witnesses.

EDWIN Z. MACK.
